VENDING MACHINE

Charles R. Spare and Charles H. Lapsley,
Philadelphia, Pa.

Application May 25, 1937, Serial No. 144,654

2 Claims. (Cl. 312—36)

Our invention relates to a new and useful vending machine and more particularly to a coin-controlled vending machine especially adapted for the display and sale of packaged goods with 5 unlimited individual selectivity.

Our invention still further relates to a vending machine of an extremely simplified construction in which, by means of a single delivery opening and by means of a single coin-control device a 10 very great, and for all practical purposes, unlimited variety of packaged material may be dispensed.

Our invention still more particularly relates to a vending machine of this character especially 15 fitted for displaying and selling bottled drinks (which are usually refrigerated) automatically and selectively.

Vending machines heretofore have been made for dispensing bulked or packaged goods or beverages, but in all of these machines as far as we are aware, there was a separate compartment and a separate coin-control mechanism for vending the goods in said compartment. Thus, if a 20 package of one brand of cigarettes is desired, the money is deposited in a slot corresponding to that brand, and, if another brand is desired, the money is deposited in a different slot. The same is true in such beverage vending machines as have been attempted, which, as far as we know, have not 25 only had the disadvantage of having a multiplicity of compartments, but which also have not been capable of dispensing bottled beverages which are more desirable since they are sealed and sanitary and since the public prefers packaged 30 goods put out by a manufacturer who commands their good will to bulk merchandise especially in beverages, the origin and preparation of which may be doubtful.

To the above ends our invention consists generally of a trough adapted to receive a refrigerant such as ice, said trough being accessible for drainage and replenishment of the refrigerant without affording access to the bottled beverage being sold. Positioned within and communicating 40 with said trough is a rotary receptacle in which any number of bottles containing different or the same kind of beverage are positioned in a staggered order, means for rotating said receptacle selectively to bring the desired bottle in registration with the delivery opening, and a coin-control device for permitting the opening of the door normally closing said opening only when a single bottle is in proper registration for delivery through said opening, the opening of said door 45

serving automatically to lock said rotary receptacle against further movement.

Our invention further provides means for the return of any coins deposited in the machine and not conforming to the specification of the coin 5 intended to effect delivery of a bottle.

The full nature and advantage of our invention will be more clearly set forth in the following specification and in connection with the accompanying drawings in which:

Fig. 1 represents a plan view of a vending machine embodying our invention.

Fig. 2 represents on an enlarged scale a section on line 2—2 of Fig. 1.

Fig. 3 represents a section on line 3—3 of Fig. 2. 15

Fig. 4 represents on an enlarged scale a view partly in section and partly in elevation on line 4—4 of Fig. 1.

Fig. 5 represents a section on line 5—5 of Fig. 4.

Fig. 6 represents a view partly in plan and 20 partly in section on line 6—6 of Fig. 4.

Fig. 7 represents on an enlarged scale a section on line 7—7 of Fig. 1.

Referring to the drawings in which like reference characters represent like parts and more 25 particularly to Fig. 2 our novel vending machine includes a box or receptacle of any desired size or shape and formed of the vertical walls 1 and bottom 2 which are suitably insulated. The receptacle is provided with a top cover 3 which is suitably secured to the vertical walls in a permanent or detachable manner. The cover 3 has an extension 8 which is hinged at 10 and which may be locked shut at 11. The extension 8 is opened in order to admit cracked ice or other refrigerant to the interior of the receptacle and, if the lock 11 is used, the service man has a key to it, or the lock 11 may be omitted and a simple latch which permits instantaneous access to the interior of the box may be substituted.

In the receptacle 12 is a trough 12 which is divided by the zig-zag partition 14 into alternating staggered chambers 16 and 18 for the reception of the bottles 20 or 21. The trough 12 may be formed of perforated, 30 vertical and/or bottom walls so that the cracked ice or other refrigerant may have direct access to the bottles 20 or 21, or the trough 12 may be in the nature of an open frame work or the like.

22 designates supporting legs provided with the rollers 24 which carry the weight of the trough 40 12 with the bottles positioned therein so as to make the latter more freely rotatable. The cover 3 is provided with a central cut-out or opening which is closed in part with the plate glass or other transparent sections 28 through which the 45

ice or other refrigerant may have direct access to the bottles 20 or 21, or the trough 12 may be in the nature of an open frame work or the like.

22 designates supporting legs provided with the rollers 24 which carry the weight of the trough 50 12 with the bottles positioned therein so as to make the latter more freely rotatable. The cover 3 is provided with a central cut-out or opening which is closed in part with the plate glass or other transparent sections 28 through which the 55

tops of the bottles 20 and 21 may be seen. The trough 12 is provided with a hub 30 which extends upwardly through an opening in the cover 3 and to which is keyed at 34 the disc 36 which is provided with the handle 38. 31 designates a sleeve bearing having the flange 32 by which it is suspended from and secured to the cover 3 (see Fig. 2). Between the periphery of the disc 36 and the flange 32 is the ball bearing or other anti-friction element 40, partially supporting the disc 36, hub 30 and trough 12 and facilitating the rotation of said trough, it being noted that the trough 12 is supported primarily by the anti-friction bearings 24. 42 designates a fixed arm carried by the hub sleeve bearing 31 and supporting a spring-pressed ball 44 which is adapted to engage any one of a series of notches 46 in the horizontal flange 47 of the hub 30 temporarily to hold the trough 12 in position for a purpose hereinafter set forth. Mounted on the cover 3 is an auxiliary cover 50 which is hinged at 52 and which may be locked to the adjacent vertical wall of the container at 54. On the cover 50 is mounted a coin-control mechanism 56 adapted to open a delivery door 58 hinged at 60 and provided with a transparent portion 62.

Referring to Fig. 4 in which the operation and structure of the coin-control mechanism is diagrammatically illustrated, the coin 63, such as a five cent piece, is deposited through the slot 64 through which it drops into the coin compartment 66, formed of the strip 67 carried by the rocker arm 74. The upper end of the strip 67 is deflected as at 69 to obstruct the opening 64 and prevent insertion of a coin 63 while the rocker arm is in the position shown in dotted lines in Fig. 4. If the coin is too small such as a penny or dime, it will pass through the compartment 66, and, if it is too big, it cannot enter the compartment 66, and in either event it falls out onto the inclined guide way 68 to be discharged through the coin return opening 69. If the coin is of the proper size it is retained in the compartment 66 so that, when the lever 70 which is pivoted at 73 is moved in the direction of the arrow 71, the lug 72 on the arm 70, moves through the slot 75 in the partition 77 and engages the edge of the coin 63 and interlocks the operating lever 70 with the rocker arm 74 which is pivoted at 74x to the partition 77, it being understood that in the absence of a coin in the compartment 66 the lever 70 can be reciprocated in the slot 75 without in any way affecting the rocker arm 74, the size of the lug 72 being such as to clear the arm 74 in the absence of a coin in the compartment 66. The movement of the lever 70 from the position indicated at A to the position indicated at B moves the rocker arm 74 from the position at C to that indicated at D. This moves the pin 76 at the lower end 78 of the rocker arm 74 thru the horizontal slot 80 and up in the inclined slot 82. When the pin 76 is travelling in the slot 82 it pushes the link 84 in the direction of the arrow 83. This brings the shoulder 86 of the link 84 to bear against the edge of the door 58 and raises it from the closed position shown at E to the partially open position shown at F. With the door 58 only partly open, as shown at F, it is not possible to withdraw either of the bottles 20 or 21 that may be in registration therewith, so that it is necessary for the purchaser to push the door open further from the position shown at F to the position shown at H. When the door 58 reaches the position H it pulls the rocker arm 74 a little further in the direction of the arrow 88, that is,

enough to make the rocker arm 74 clear the lever 70 when the latter is in the position B. This releases the coin 63 interlocked between the lever 70 and the rocker arm 74 and permits it to drop into the coin box 90. The door 58 is now fully open and the bottle registering therewith can be removed.

Referring now to Fig. 7, it will be seen that the door 58 is secured at its hinge 60 to the cam 92 which rides on the roller 94 mounted in the U-shaped head of the pin 96. The pin 96 is normally retained in its upper position by the spring 98, but, when the door 58 is open as at H, the cam 92 forces the pin 96 downwardly into engagement with one of the notches 46 that happens to be in registration therewith as shown in Fig. 2, thus locking the trough 12 against further rotation and preventing the withdrawal of any bottle 20 or 21 other than that registering with the door and authorized to be removed. When the bottle has been removed the door 58 drops shut by its own weight and again assumes the horizontal position shown in Fig. 2 thus returning the rocker arm 74 to the position C in solid lines in Fig. 4. In this position it is impossible to open the door without dropping a coin and manipulating the lever 70 as described, for the reason that the pin 76 would, if an attempt to open the door is made, bear downwardly in the horizontal slot 80 against the horizontal extension 100 in the direction of the arrow 102. As seen from Figs. 1 and 4 the lever 70 is movable in the slot 78 formed in the coin-control box casing.

While the vending machine has been shown as specifically applied to the sale of refrigerated drinks in bottled form, it is to be understood that it is not limited to that use alone, for, if desired, it can be used for the vending of other packaged material such as boxed candy or the like and that it can further be used for selling hot drinks during the winter time by the substitution for the refrigerant in the outer receptacle and surrounding or communicating with the trough 12 of a steam coil or other heating medium. A still further adaptation of this vending machine is also contemplated in the sale of multiple packages of the same kind but individually or one at a time which can be accomplished by placing, where the bottles 20 and 21 are, stacks of packages such as one kind of cigarettes in one compartment and another in the next and so on. Similarly, it can be used for dispensing or serving lunches, hot or cold, of the same or of different kinds. The glass windows formed in the cover 3 are made wide enough to afford full visibility but are nevertheless made narrow enough to prevent the withdrawal of either of the bottles 20 or 21 so as to remove the incentive for breaking the glass in an effort to pilfer a bottle.

Having thus described our invention, what we claim as new and desire to secure by Letters Patent is:

1. A vending machine comprising a casing, a cover therefor, a rotatable trough, rollers for supporting said trough on the bottom of said casing, a hub extending from the top of said trough through said cover whereby said trough may be rotated from without said casing, oppositely disposed pendant brackets carried by said cover, a ball carried by one of said brackets, a vertically slidable pin carried by the other of said brackets, there being a plurality of circularly disposed recesses in the top of said trough adapted to be engaged by said ball and said pin, a spring carried by said first named bracket above said ball for

successively forcing said ball in engagement with said recesses, a spring secured around, and normally retaining said pin out of engagement with said recesses, a hinged delivery door carried by said cover, and a cam carried by the hinged end of said door and riding on the upper end of said pin whereby, when said door is opened, said cam depresses said pin into engagement with one of said recesses to prevent rotation of said trough as long as said delivery door is open.

2. A vending machine comprising a casing, a cover therefor, a rotatable trough, rollers for supporting said trough on the bottom of said casing, a hub extending from the top of said trough through said cover whereby said trough may be rotated from without said casing, oppositely disposed pendant brackets carried by said cover, a ball carried by one of said brackets, a vertically slidable pin carried by the other of said brackets,

there being a plurality of circularly disposed recesses in the top of said trough adapted to be engaged by said ball and said pin, a spring carried by said first named bracket above said ball for successively forcing said ball in engagement with said recesses, a spring secured around, and normally retaining said pin out of engagement with said recesses, a hinged delivery door carried by said cover, a cam carried by the hinged end of said door and riding on the upper end of said pin whereby, when said door is opened, said cam depresses said pin into engagement with one of said recesses to prevent rotation of said trough as long as said delivery door is open, and a vertical zigzag partition dividing said trough into an inner and outer series of annularly-disposed staggered compartments.

CHARLES R. SPARE.
CHARLES H. LAPSLEY.
